(57) **CLAIM**

The ornamental design for a head mounted display visor, as shown and described.

DESCRIPTION

FIG. 1 is a front perspective view of an embodiment of a head mounted display visor, shown mounted to a head mounting harness.

FIG. 2 is a rear perspective view of the visor of FIG. 1.

FIG. 3 is a front elevation view of the visor of FIG. 1.

FIG. 4 is a rear elevation view of the visor of FIG. 1.

FIG. 5 is a right side view of the visor of FIG. 1.

FIG. 6 is a left side view of the visor of FIG. 1.

FIG. 7 is a top plan view of the visor of FIG. 1.

FIG. 8 is a bottom plan view of the visor of FIG. 1.

FIG. 9 is a front perspective view of another embodiment of a head mounted display visor, shown mounted to a head mounting harness.

FIG. 10 is a rear perspective view of the visor of FIG. 9.

FIG. 11 is a front elevation view of the visor of FIG. 9.

FIG. 12 is a rear elevation view of the visor of FIG. 9.

FIG. 13 is a right side view of the visor of FIG. 9.

FIG. 14 is a left side view of the visor of FIG. 9.

FIG. 15 is a top plan view of the visor of FIG. 9; and,

FIG. 16 is a bottom plan view of the visor of FIG. 9.

The broken lines in the drawings depict environmental structure and form no part of the claimed design. However, in embodiments other than those illustrated, lines that are currently illustrated as broken may be redrawn as solid lines, and lines that are currently illustrated as solid may be redrawn as broken lines. The scope of the present disclosure encompasses all lines illustrated, whether broken or solid.

1 Claim, 16 Drawing Sheets
